UNITED STATES PATENT OFFICE.

ALBERT P. LEE, OF CHICAGO, ILLINOIS, ASSIGNOR TO LEE LOADER & BODY CO., OF CHICAGO, ILLINOIS.

DUMPING-HOPPER.

1,334,913.

Specification of Letters Patent. Patented Mar. 23, 1920.

Application filed October 31, 1918. Serial No. 260,471.

To all whom it may concern:

Be it known that I, ALBERT P. LEE, a citizen of the United States, residing at Chicago, in the county of Cook, and State 5 of Illinois, have invented a certain new and useful Improvement in Dumping-Hoppers, of which the following is a full, clear, concise, and exact description, reference being had to the accompanying drawings, forming 10 a part of this specification.

My invention relates to dumping hoppers and more particularly to that class of hoppers which are adapted to roll on a runway from a central charge carrying to a limiting dumping position upon either side of the central position. My invention concerns itself more particularly with the means which hold the hopper in its central charge carrying position. The means which 20 I employ are exceedingly simple and are very effective to hold the hopper not only against rolling from side to side but also to hold the hopper upon the runway when the vehicle upon which it is placed rides over 25 obstructions. In the preferred form of the invention holding means are duplicated at the two ends of the hopper and are so arranged that they move conjointly. I will describe one form which my invention may 30 take more in detail by referring to the accompanying drawings illustrating such embodiment in which—

Figure 1 is a side view of a hopper provided with my improved holding mechanism;

Fig. 2 is an end view thereof, the hopper being shown in one of its limiting positions in dotted lines;

Fig. 3 is a sectional view on line 3, 3 of 40 Fig. 2; and

Fig. 4 is a sectional view on line 4, 4 of Fig. 2 certain parts being broken away more clearly to reveal features of construction.

In the drawings I show a hopper 10 operating upon runways 11. This hopper when in its charge carrying position occupies the position shown in full lines in Fig. 2 and occupies the dotted position when in its dumping position at the right hand 50 extremity of the runway. The runway is shown mounted upon a suitable frame work 12 which can in any manner be mounted upon the vehicle or form a part of the vehicle as shown. The hopper has rails 13 to 55 coöperate with the runways 11. My im-

proved holding means consists of a pair of brackets 14 and 15 these brackets consisting of two strips 16 and 17 preferably of angle iron, which are pivoted upon a stud or shaft 18. The shaft 18 is carried in the 60 frame work 12. The upper extremities of the strips 16 and 17 are united by two straight strips of angle iron to form cross pieces, respectively the strips 19 and 20. The hopper ends are each provided with 65 coöperating angle iron strips 21 which interlock as more clearly shown in Fig. 3. A small section of T-iron 22 is riveted to the angle iron section 21 and is provided with a slot 23 into which the protruding tongue 70 of the strip 20 may project. When the brackets are in the position shown in Figs. 1, 3 and 4 it will thus be seen that they interlock with the locking elements 21 and 22 provided upon the hopper ends. In order to 75 release the hopper the brackets 14 and 15 are swung outwardly as shown in dotted lines in Fig. 1. In order to swing these brackets simultaneously I provide suitable means which may, for instance, consist of 80 the tension elements 24 and 25. These are linked at their extremities to the brackets 14 and 15 respectively. As the pivotal point of the brackets lies between the mounting point of the elements 24 and 25 85 it will readily be seen that as one bracket is swung outwardly the other bracket must follow suit. A strong spring 26 normally holds the brackets in their locking position. From the above description the nature of 90 my device will be readily apparent to those skilled in the art and its simplicity will be peculiarly apparent. I have herein described but one form which my invention may take but claim as my invention all such 95 forms as are within the scope of the appended claims.

I claim:

1. In a device of the character described, the combination with a runway, of a rolling 100 hopper movable thereon, and means for holding said hopper in its central position upon said runway, said means including a pair of vertical interconnected tiltable brackets pivoted near their lower ends and 105 mounted at opposite extremities of said hopper, movable in opposite directions toward and away from said hopper.

2. In a device of the character described, the combination with a runway, of a roll- 110

- ing hopper movable thereon, and means for holding said hopper in its central position upon said runway, said means including a pair of vertical tilttable brackets pivoted near their lower ends and mounted at opposite extremities of said hopper movable toward and away from said hopper, and means for causing the simultaneous movement of said brackets.
- 10 3. In a device of the character described, the combination with a runway, of a rolling hopper movable thereon, and means for holding said hopper in its central position upon said runway, said means including a 5 pair of tilttable brackets mounted at opposite extremities of said hopper movable toward and away from said hopper, and a link uniting said brackets to cause the movement of said brackets simultaneously in opposite directions.
- 15 4. In a device of the character described, the combination with a runway, of a rolling hopper movable thereon, and means for holding said hopper in its central position upon said runway, said means including a pair of tilttable brackets mounted at opposite extremities of said hopper movable toward and away from said hopper, said brackets having cross pieces and the ends of 20 said hopper having coöperating cross pieces to interlock with the cross pieces upon said brackets.
- 25 5. In a device of the character described, the combination with a runway, of a rolling hopper movable thereon, and means for holding said hopper in its central position upon said runway, said means including a pair of tilttable brackets mounted at opposite extremities of said hopper movable toward and away from said hopper, and means for 30 causing the simultaneous movement of said brackets, said brackets having cross pieces and the ends of said hopper having coöper- 35
- ating cross pieces to interlock with the cross pieces upon said brackets. 45
6. In a device of the character described the combination with a runway, of a rolling hopper movable thereon, and means for holding said hopper in its central position upon said runway, said means including a pair of tilttable brackets mounted at opposite extremities of said hopper movable toward and away from said hopper, and a link uniting said brackets to cause the movement of said brackets simultaneously in opposite directions, said brackets having cross pieces and the ends of said hopper having coöperating cross pieces to interlock with the cross pieces upon said brackets. 50
- 10 7. In a device of the character described, the combination with a runway of a rolling hopper movable thereon, a shelf projecting from each extremity of said hopper, a pair of tilttable brackets having a shelf adapted to coöperate with the corresponding shelf upon the hopper for holding said hopper in its central position, and tongue and groove means provided upon said hopper and brackets to further lock said hopper in its central position. 55
- 15 8. In a device of the character described, the combination with a runway, of a rolling hopper movable thereon, means for holding said hopper in its central position upon said runway, said means including a pair of interconnected tilttable vertical brackets pivotally mounted at opposite extremities of said hopper with their upper ends movable in opposite directions toward and away from said hopper, and means for holding said brackets in operative position. 60
- 20 In witness whereof I hereunto subscribe my name this 16th day of October, A. D. 1918.

ALBERT P. LEE.
